UNITED STATES PATENT OFFICE.

CLARENCE F. HEATH, OF WASHINGTON, DISTRICT OF COLUMBIA.

LETTER-CARRIER'S DESK.

1,376,333.

Specification of Letters Patent. Patented Apr. 26, 1921.

Application filed April 21, 1917. Serial No. 163,634.

To all whom it may concern:

Be it known that I, CLARENCE F. HEATH, a citizen of the United States, residing at Washington, in the District of Columbia, 5 have invented certain new and useful Improvements in Letter-Carriers' Desks, of which the following is a specification.

This invention relates to post-office furniture and especially to letter carriers' desks 10 which are used for sorting and routing mail preparatory to being delivered.

The main object of my invention is to provide an improved desk and routing case which will greatly facilitate the sorting and 15 routing of the mail. To this end I provide separate compartments or sections of the desk for letters and for papers and I make the desk exceedingly compact by having the paper receiving section perpendicular to the 20 letter receiving section and arranged to slide forwardly into operative position and rearwardly at the side of the other section when not in use. The shelves are open at the front and back in order that the desk may 25 be easily cleaned and kept strictly sanitary. The wire-formed partitions are carried by the shelves and those in the letter section may be provided with a forwardly projecting guiding nose or lip to assist in guiding 30 the letters into the proper pigeon-hole or compartment and indicating the separating line between adjacent compartments. Furthermore I make the shelves slidable so that after the mail has been sorted the shelves 35 may be pushed back until the letters project and overhang the front edges of the shelves which permits them to be more readily withdrawn. This feature results in a very great saving of time and greatly facilitates the 40 handling of the mail.

The several features above referred to, together with other improvements will be understood from the following description in connection with the accompanying drawings, in which Figure 1 is an end elevation 45 taken from the side opposite the paper sorting section; Fig. 2 is a vertical section through the letter sorting section; Fig. 3 is an enlarged fragmentary longitudinal section through the lower part of the paper sorting section and the table top; and Fig. 4 is a detail view showing the use of the wire partitions; Fig. 5 is a fragmentary perspective showing the removable letter section; 50 and Figs. 6 and 7 are top plan and longitudi-

dinal sectional views of another form of paper rack or slide.

The table 1 is of some suitable or usual construction on which the mail is received while it is being sorted. 60

The routing or sorting case comprises two sections, one for the letters and the other for the papers and packages, each consisting of a series of shelves divided into compartments by wire partitions. I prefer to make 65 the bottom tier of compartments in the letter section 5 in the form of a unitary box or section 6, open at the front and back and divided into a number of pigeon-holes by fixed partitions 8, which preferably extend 70 from the back to within a short distance of the front. This pigeon-hole box or section is removable and can be taken out when desirable to add to the space on the top of the table. I prefer to close the case at the 75 back of the section by a solid board 7, as shown in Fig. 5.

Each pigeon-hole and also each shelf 9, is divided into a number of compartments by wire partitions 10, the vertical ends of the 80 wires fitting into holes in the shelves. If the mail in any building or to any firm or individual on the carrier's route is quite large, the compartment assigned to that building, firm or individual, may be enlarged by removing one or more of the wire 85 partitions. In fact an entire pigeon-hole may be made into a single compartment by removing all of the wire partitions therefrom. 90

Each of the shelves 9 slides in grooves in the upright ends 14, and is readily removable. Stops 15 limit the rearward movement of the shelves. Bars 17, fastened by cleats 18, or in any suitable manner, are 95 placed slightly above the shelves and at a short distance from the back to serve as stops against which the letters abut as they are slid into the compartments.

One form of the partitions shown at 20 100 consists of wires bent into a loop and formed with a tongue or nose 21, projecting horizontally toward the front, the ends of the wire being inserted in holes in the top of the shelf. The parts are so proportioned 105 that the tongues 21 project nearly flush with the front ends of the letters when the shelves are in their forward position as shown in Fig. 2, serving to indicate the division lines between the compartments 110

when said compartments are full of mail and also as guides for the letters as they are inserted in the compartments. The lower ends of the loops adjacent the top of the shelves prevent the letters from sliding into the adjacent compartments. I have shown another form of wire partition at 23, in which the front leg of the loop extends upwardly from the shelf substantially vertically a distance equal to about one-half the width of an ordinary envelop, and then extends rearwardly horizontally for about an equal distance; the wire being then bent into an upwardly extending loop about three inches in height so that its top edge is slightly below the top edge of the ordinary envelops, the rear leg of the wire sloping rearwardly in an oblique direction. In this form of partition the front vertical leg is preferably slightly back of the front edge of the shelf and forms a guide for the letters as they are inserted, the letters being further guided by the horizontal portion, the upwardly extending loop and the oblique rear leg. The inclined rear leg of the partition effectually prevents the letters from passing into the adjacent compartment.

In prior sorting and routing cases or desks, a single rack has been employed for both letters and papers. In some instances the lower shelves have been used for letters and the upper shelves for papers, but in any event, this necessitated a higher rack than is convenient or desirable in order to provide sufficient space for the mail, especially upon heavy routes. In my sorting and routing desk, I provide a separate rack for papers which is arranged at one end of the desk, thus revolutionizing the method of handling the enormous amount of paper mail handled in the post office and thereby causing a great saving of time. The paper rack comprises a case 30 provided with a number of removable shelves 31 which slide in grooves in the end uprights of the case and abut at their rear edges against transverse stops 34. The shelves are divided into compartments by means of wire loop partitions 35 having their ends secured in holes in the top sides of the shelves forming much wider compartments than are used in the letter rack. Transverse horizontal stops 36 serve as back stops for the papers and also serve to brace the uprights and make the case more rigid. The bottom member 38 of the paper rack is provided with means for slidably engaging the top of the table extension 39 and which also serves to securely hold the rack when it is slid into its forward position, indicated in dotted lines in Fig. 1 with the forward end overhanging the table extension 39. As one means of accomplishing this function I have shown the bottom member 38 provided with a depend-

ing dove tail projection 40 which is adapted to slide in a dove tail groove in the table 39. The dove tail piece 40 may extend partially along the bottom of the member 38 as indicated in Fig. 6 so that it may be positioned in the forward and rearward positions by abutting against the front stop 41 and the rear stop 42 respectively. The desk arm 45 at the right hand end of the table may extend the full width of the table top but the arm 46 upon the other side which is adjacent the paper rack is shorter and of a width to extend from the letter-rack to the rear end of the paper rack when the latter is drawn outwardly into its forward position, in order that the arm may not interfere with access to the compartments on the lower shelf of the paper rack.

The operation of my letter and paper sorting and routing desk will be understood from the foregoing detailed description of the construction. When it is desired to sort the mail which has been laid upon the table of one of the desks, the paper-rack is drawn forward into the position shown in Fig. 2 and indicated in dotted lines in Fig. 1, the front end of the dove tail member 40 being then in engagement with the front stop 41. The entire set of racks, both for the letters and for the papers and packages are thus within easy reach of the letter carrier, none of the shelves being so high as to be difficult to reach. I have found that this arrangement greatly facilitates the sorting and distribution of mail and results in a considerable saving of time. Moreover by bringing all of the shelves within easy reach, less effort is required and the work is correspondingly less tiresome. During the sorting operation, the shelves 9 of the letter-rack remain in their forward position, the front edges of the shelves being substantially flush with the front of the letter-case as indicated in Fig. 5. As previously stated, the horizontally projecting nose or lip portions 21 serve to indicate the position of the separating partitions and also assist in guiding the letters into the compartments. The rear ends of the letters are arrested by the stops 17 and ordinarily leave the nose members 21 nearly flush with the forward ends of the letters. Letter carriers especially will appreciate the advantages of this arrangement. When the partitions 23 are employed, having the horizontal portion 23^a, there is no danger of the unusually small envelops falling sidewise into adjacent compartments. When partitions 20 are employed, I prefer to place the nose member 21 in a position where it will strike the lower part of the letters as they are inserted into the compartments. A very material advantage, and perhaps the most important reason for locating the bottom of the com-

partments is that the position does not interfere with the free space which is desirable and facilitates the rapid distribution of the mail. It will be observed that while 5 the narrow guiding tongue member 21 extends nearly flush with the front of the case or rack, the front part of the main body of the loop 20 is spaced back a considerable distance therefrom to thus leave 10 the front part of the space between the shelves unobstructed. These features are quite important and will be appreciated by letter carriers in general.

After the paper mail has been assorted 15 the carrier pulls it from the shelves and lays it in proper order and then fastens it into a bundle by means of a strap. It will be found convenient first to extend the strap across the table 1 and in order that 20 the buckle on the strap will not be in the way, I may provide a hole 50 in the arm 45, through which the buckle may project. After the papers have been strapped up and out of the way the carrier proceeds to 25 draw and strap up his letters. The shelves 9 are pushed rearwardly until they engage the back strips 15 and are in a position indicated in Fig. 4. The letters, however, will be held by the stops 17 so that the 30 shelves will slide beneath them and be left with their front ends overhanging the shelves and projecting in front of the guide 21, or the front leg of the form 23. This greatly facilitates the withdrawal of the 35 letters as their front ends may much more readily be grasped when the shelves and partitions have been pushed back out of the way.

After the mail has been withdrawn from 40 the racks, the paper-rack may be pushed back into the position shown in Fig. 1, the movement being arrested by the dove tail 40 striking the rear stop 42.

Instead of the form of paper rack shown

in Fig. 1, I may provide an open top shelf 45 shown in Figs. 6 and 7, especially when the mail is light. This may consist of a sliding shelf 56, having upright members 57, 58 along one side and at the rear end, and preferably with a low upright 59 at the 50 front end.

This may be slid forward in the same manner as the paper rack described in connection with Fig. 1. For this purpose the bottom of the shelf may be provided with a 55 depending T-shaped member 60 adapted to slide in the slot 61 as the shelf is drawn forward, the front part of the shelf being guided by a block 62, on the table moving in a slot 63 in the bottom of the shelf. 60

I have described in detail the particular construction illustrated in the accompanying drawings for the purpose of clearly disclosing an embodiment of my invention but it will be evident to engineers and 65 skilled mechanics that the various changes and modifications may be made within the scope of my claims and without in any manner departing from the spirit of my invention. 70

I claim:—

In a routing case, the combination with a plurality of shelves, of partitions therefor dividing the shelves into compartments, each partition comprising a wire bent into substantially U-shape, the ends being inserted into the upper side of the shelves, the front leg of the partition member being formed with an intermediate horizontally extending portion to serve as a guide for the mail 75 matter, the lower ends of the wire preventing the mail matter from sliding into adjacent compartments, and the rear leg being inclined rearwardly to serve as a guide for the mail matter as it is being inserted. 80 85

In testimony whereof I affix my signature.

CLARENCE F. HEATH.
